UNITED STATES PATENT OFFICE

100,436

DESIGN FOR A WATERPROOF FABRIC

Fred L. Meneley, La Crescenta, Calif.

Application December 19, 1935, Serial No. 60,180

Term of patent 3½ years

To all whom it may concern:

Be it known that I, Fred L. Meneley, a citizen of the United States, residing at La Crescenta, in the county of Los Angeles and State of California, have invented a new, original, and ornamental Design for a Water-Proof Fabric, of which the following is a specification, reference being had to the accompanying drawing forming a part thereof.

Figure 1 is a front elevational view of a piece of water-proof fabric showing the design unit, except for the portion between the break lines

which is similar to that on either side thereof, and which unit may be repeated in horizontal relation over the surface of the fabric.

Fig. 2 is a vertical sectional view thereof.

I claim:

The ornamental design for a water-proof fabric, as shown and described.

Signed at Los Angeles, in the county of Los Angeles and State of California, this 16th day of December, 1935.

FRED L. MENELEY.
